THERMOSTATICALLY CONTROLLED MEANS
FOR ROTATING PACKING CUPSJohn C. Cox, St. Louis, Mo., assignor to Wagner
Electric Corporation, St. Louis, Mo., a corpora-
tion of Delaware

Application February 19, 1938, Serial No. 191,460

14 Claims. (Cl. 60—54.6)

My invention relates to fluid compressors and more particularly to fluid compressors of the compensating type which are employed, for example, in hydraulically actuated brakes.

These compressors (commonly referred to as "master cylinders") employ a packing cup for sealing the piston and in the form now in use in braking apparatus a porthole places the portion of the cylinder ahead of the piston in communication with a reservoir when the piston is in retracted position, whereby contraction and expansion of the fluid in the braking system due to temperature changes will not cause decrease or increase of pressure in the system.

When the piston is initially operated, a fluid pressure is developed in the cylinder ahead of the piston and packing cup and as the forward edge of the lip of the cup becomes partially positioned over the porthole, the lip will be forced sufficiently into the hole that the forward edge of the cup will rub on the forward edge of the hole as the cup is moved forward. Since in apparatus now in commercial use the same portion of a cup may pass over the porthole on many successive protractile strokes of the piston, a chafing or cutting of the cup frequently results, thus reducing the length of its effective service.

It is the object of my invention to provide thermostatically controlled means subject to the varying temperature of the fluid in the compressor for intermittently rotating the packing cup whereby the same portion thereof will not pass the porthole on all successive strokes of the piston, thus distributing the "wearing" action of the porthole over the periphery of the cup instead of permitting it to be concentrated at one point.

Other objects of my invention will become apparent from the following description taken in connection with the accompanying drawings showing two embodiments thereof. Figure 1 is a longitudinal cross-sectional view, partly in elevation, of a compressor embodying my invention, said figure also diagrammatically showing a brake mechanism as an example of apparatus which may be actuated thereby; Figure 2 is an enlarged cross-sectional view of the thermostatically controlled rotating means; Figure 3 is a cross-sectional view taken on the line 3—3 of Figure 1; Figure 4 is a longitudinal cross-sectional view of a modification; and Figure 5 is a cross-sectional view taken on the line 5—5 of Figure 4.

Referring to Figures 1, 2 and 3 in detail, numeral 1 indicates the cylinder in which is re-

ciprocable a piston 2 having a head 3, a rear flange 4, and an intermediate reduced cylindrical portion 5. Above the cylinder is a reservoir 6 cast integral with the cylinder and containing a reserve supply of fluid. The rear portion 4 of the piston engages a stop 7 to predetermine its inoperative position to which it is normally biased by a spring 8 interposed between the head of the piston and the forward end of the cylinder. The rear end of the cylinder adjacent the portion 4 is provided with an annular packing cup 9 to prevent leakage of fluid from the space surrounding the reduced cylindrical portion 5.

The head 3 of the piston has associated therewith a packing cup 10 for preventing fluid from passing the piston head on the protractile stroke of the piston. The piston and cup, however, are so constructed that fluid may pass the lip of the cup during the retractile stroke of the piston and to facilitate this, the piston head 3 is formed with a plurality of passages 11 adjacent its periphery. When the piston is in retracted position, as shown in Figure 1, a compensating porthole 12 places the reservoir in communication with the portion of the cylinder ahead of the piston and the packing cup. A passageway 13 is also provided between the reservoir and the portion of the cylinder at the rear of the head of the piston in order that the space surrounding the reduced cylindrical portion 5 of the piston may always be filled with fluid.

The forward end of the cylinder is provided with a two-way valve structure 14 of known construction for controlling the flow of fluid to and from the cylinder. The dome part of the valve structure is wedged into the end of the spring 8 to prevent relative rotation between these members and the valve structure is prevented from rotating relatively to the cylinder by a projection 50 cooperating with a slot 51 in a guide ring 52. The cylinder is connected by a suitable conduit 15 to the conduits 16 leading to the actuating cylinders 17 of the brake assemblies 18 (only two being diagrammatically shown). The piston 2 is actuated by a piston rod 19 which may be controlled by a pedal (not shown) in the usual manner.

With the structure just described, when the piston is moved forward, the compensating porthole 12 will first be cut off and then fluid under pressure will be forced through the holes 20 of the two-way valve device 14 and into the brake line. When the piston is allowed to retract, fluid will be forced back through the brake lines into

the cylinder by the action of the return springs of the brake assemblies, the two-way valve structure unseating against the action of spring 8 to permit the fluid to re-enter the cylinder. In this type of compressor, the compensating port-hole 12 is kept as small as possible but for reasons already pointed out, the inner edge thereof causes considerable chafing or cutting of the lip of the cup as the cup is moved forward over the open end of the porthole. This continued "wearing" of the cup at a single point results in a short life for the cup which would be considerably prolonged if the effect thereof could be distributed over the periphery of the cup.

In accordance with my invention, I provide thermostatically controlled means for rotating the packing cup relative to the cylinder wall, thus preventing the same portion of the lip of the cup from passing over the porthole on all successive strokes of the piston. The head 3 of the piston is provided with a plurality of recesses 21 and the rear surface of the packing cup 10 is formed with a like number of projections 22 which are adapted to snugly fit into the recesses, thus so connecting the cup and the piston that the two will rotate together. The forward face of the cup has secured thereto a member 23 by means of prongs 24. The central part of the member is formed with a square portion 25 having a conical tip and cooperating with member 23 is a cup-shaped member 26 having a recess for mounting on the conical tip of portion 25 where it is held by spring 8. The cup-shaped member 26 is so constructed as to wedge into the end coil of spring 8 so that relative rotative movement between these two members is prevented. The inner cylindrical surface of the cup-shaped member 26 is formed with a plurality of teeth 27 and mounted on the square portion 25 of member 23 is a spiral-shaped temperature sensitive element 28 of the bimetallic type provided with a detent end 29 for cooperation with teeth 27.

The fluid in the cylinder surrounds the element 28 and this fluid is subjected to the changes in temperature due to atmospheric changes and also the changes in temperature due to the operation of the brake assembly since the fluid motors 17 are adjacent the brake drum.

As the temperature of the fluid rises, the spiral temperature sensitive element 28 will tend to "wind up" in a clockwise direction, as seen in Figure 3, and since the detent end engages teeth 27, the resulting effect will be to cause member 23 to rotate relative to the cup-shaped member 26 as the latter member is held against rotation by the action of spring 8 in a manner already described. Since member 23 is secured to the cup, the cup will, therefore, be rotated relative to the cylinder wall, thus placing a different portion of the lip of the cup in position for movement over the compensating port. The rotation of the packing cup will generally take place after the cup becomes positioned rearwardly of the compensating porthole since at this time there is no fluid pressure acting on the lip of the cup to hold it in tight frictional engagement with the cylinder wall. At this time spring 8 is exerting a minimum retracting force on the piston. Consequently, the "wearing" on the cup will not all take place at one point but will be distributed about the periphery of the cup, thereby prolonging the life of the cup.

When the fluid in the cylinder cools, the spiral element will tend to "unwind" but since the de-

tent end is free to move over teeth 27 in this direction of movement, no relative movement will take place between members 23 and 26. The detent will thus be placed in cooperative relation with a different tooth for turning the packing cup when the temperature of the fluid again increases. It is thus seen that the cup will be intermittently rotated, the intervals at which such rotation takes place depending upon the time and extent of changes in the temperature of the fluid.

Referring to the modification shown in Figures 4 and 5, the piston head 3' is formed with a cylindrical recess 30 in which is press-fitted a cylindrical ring 31 provided with teeth 32 on its inner surface. The forward edge of recess 30 is beveled for cooperation with a disk 33 having an annular beveled surface 34. When the two beveled surfaces are in contact, the forward end of passages 35 extending through the piston head will be closed, thus preventing fluid from flowing from the rear of the head of the piston to the portion of the cylinder ahead of the piston. The disk 33 has secured thereto two pins 36 and 37 which project into the recess 30 of the piston head and mounted on these pins is a temperature sensitive element in the form of an S-shaped bimetallic element 38 (Figure 5). One end of the bimetallic element is formed with a detent 39 for cooperation with teeth 32 for preventing the disk from rotating in a counter-clockwise direction (Figure 5) and the other end of the element is provided with a detent 40 for cooperation with teeth 32 for preventing this end from also moving in a counter-clockwise direction.

The piston packing cup 41 has formed on its rear surface a plurality of projections 42 which project into holes 43 in the forward surface of disk 33, thus connecting the disk and cup for rotation as a unit. The forward surface of the cup cooperates with a bearing plate 44 having a central protuberance 45 for receiving the recessed portion of a member 46 engaged by the end of spring 8 which returns the piston to its normally inoperative position. The piston 2 is held against rotation by providing the end of the piston rod 19 with a prong 47 for engagement in a slot 48 in the piston.

In the structure just described, if there is a rise in temperature of the fluid in the cylinder, the U portion of the bimetallic element 38 will tend to "open up" but since detent 40 cannot move because it engages one of the teeth 27, the result will be a clockwise rotation of disk 33 relative to piston 2. Under these conditions, detent 39 will slide over teeth 32. As the cup is secured to the disk, it will be rotated relative to the cylinder wall, thus presenting a different portion of the periphery of the cup for movement past the compensating porthole 12 when the piston is moved forward. When the temperature of the fluid decreases, detent end 40 of the thermostatic element will be moved toward the portion supported by pins 36 and 37 and since detent 39 will not permit the disk to move counter-clockwise, detent 40 will be drawn over one or more of teeth 32 depending upon the amount of decrease in temperature.

If during the retractile stroke of the piston there is a tendency for a subatmospheric pressure to become established ahead of the cup, fluid will be free to flow through the piston head passages 35, past disk 33 and the periphery of the cup since, under these conditions, the co-

operating beveled surfaces of disk 33 and the piston head will move sufficiently apart to permit fluid to pass between the surfaces.

Being aware of the possibility of modifications in the particular structure herein described without departing from the fundamental principles of my invention, I do not intend that its scope be limited except as set forth by the appended claims.

10 Having fully described my invention, what I claim as new and desire to secure by Letters Patent of the United States is:

1. In apparatus of the class described, a cylinder, a piston reciprocable in said cylinder, a packing cup for the head of the piston, and thermostatically controlled means for rotating the cup relative to the cylinder wall.

2. In apparatus of the class described, a cylinder, a piston reciprocable in said cylinder, a packing cup for the head of the piston, and thermostatically controlled ratchet means for intermittently rotating the cup relative to the cylinder wall.

3. In apparatus of the class described, a cylinder, a piston reciprocable in said cylinder, a packing cup for the head of the piston, and thermostatically controlled means cooperating with the cup and the piston for rotating the cup relative to the cylinder wall.

30 4. In apparatus of the class described, a cylinder, a piston reciprocable in said cylinder, a packing cup associated with the head of the piston, a fluid reservoir, means including a passage in the cylinder wall and positioned ahead of the cup when the piston is in retracted position for permitting communication between the cylinder and reservoir, and thermostatically controlled means for rotating the packing cup relative to the cylinder wall when the cup assumes a position rearwardly of the passage whereby the same portion of the cup will not move past the open end of the passage on all successive strokes of the piston.

5. In apparatus of the class described, a cylinder, a piston reciprocable in said cylinder, a packing cup associated with the head of the piston, a fluid reservoir, means including a passage in the cylinder wall and positioned ahead of the cup when the piston is in retracted position for permitting communication between the cylinder and reservoir, and thermostatically controlled ratchet means for rotating the packing cup relative to the cylinder wall when the cup assumes a position rearwardly of the passage whereby the same portion thereof will not pass the open end of the passage on all successive strokes of the piston.

6. In apparatus of the class described, a cylinder, a piston reciprocable in said cylinder, a packing cup associated with the head of the piston, a fluid reservoir, means including a passage in the cylinder wall and positioned ahead of the cup when the piston is in retracted position for permitting communication between the cylinder and reservoir, a member secured against rotation, and ratchet means associated with the member and the cup for rotating the cup relative to the cylinder wall when the cup assumes a position rearwardly of the passage whereby the same portion thereof will not pass the end of the passage on all successive protractile strokes of the piston, said ratchet means including a thermostatically controlled detent.

7. In apparatus of the class described, a cylinder, a piston reciprocable in said cylinder, a packing cup associated with the head of the piston, a member secured to the packing cup, a non-rotatable member provided with teeth, and a thermostatically controlled detent mounted on the member on the packing cup and cooperating with the teeth on the non-rotatable member.

8. In apparatus of the class described, a cylinder, a piston reciprocable in said cylinder, a packing cup associated with the head of the piston, a member secured to the packing cup and provided with a pivot, a cup-shaped member positioned on said pivot and provided with teeth on its inner cylindrical surface, a spring for holding said cup-shaped member in position and preventing it from rotating, and a spiral temperature sensitive element having one end secured to the member on the packing cup and its other end provided with a detent for cooperation with the teeth of the cup-shaped member.

20 9. In apparatus of the class described, a cylinder, a piston reciprocable in said cylinder, a packing cup associated with the head of the piston, a temperature sensitive element carried by the packing cup, means forming teeth on the piston, and detent means controlled by the temperature sensitive element and cooperating with the teeth for causing the cup to be rotated relative to the piston.

30 10. In apparatus of the class described, a cylinder, a piston reciprocable in said cylinder and provided with a recessed head, a packing cup, a plate secured to the rear of the packing cup and associated with the piston head, means forming teeth on the inner wall of the recess, a temperature sensitive element carried by the plate, and detent means controlled by the temperature sensitive means and cooperating with the teeth for causing the plate and cup to be rotated relative to the piston.

40 11. In apparatus of the class described, a cylinder, a piston reciprocable in said cylinder, a packing cup for the head of the piston, and means having operatively associated parts carried by the piston and by the cup for causing the piston and cup to have intermittent relative rotation.

45 12. In apparatus of the class described, a cylinder, a piston reciprocable in said cylinder, a packing cup for the head of the piston, and thermostatically controlled means for causing the piston and cup to have relative rotation.

50 13. In apparatus of the class described, a cylinder, a piston reciprocable in said cylinder, a packing cup for the head of the piston, and ratchet means for causing the piston and cup to have relative rotation, said means embodying a thermostatically controlled pawl.

55 14. In apparatus of the class described, a cylinder, a piston reciprocable in said cylinder and provided with a recessed head, a packing cup, a plate secured to the rear of the packing cup and associated with the piston head, means forming teeth on the inner wall of the recess, a temperature sensitive element carried by the plate, and detent means controlled by the temperature sensitive means and cooperating with the teeth for causing the plate and cup to be rotated relative to the piston and the cylinder wall.

JOHN C. COX.
